UNITED STATES PATENT OFFICE.

ARTHUR BATES, ARTHUR ERNEST JERRAM, AND JOSEPH GOULDBOURN, OF LEICESTER, ENGLAND, ASSIGNEES TO UNITED SHOE MACHINERY COMPANY, OF PATERSON, NEW JERSEY, A CORPORATION OF NEW JERSEY.

SKIVING-MACHINE.

1,103,928.

Specification of Letters Patent.

Patented July 21, 1914.

Application filed September 19, 1908. Serial No. 453,813.

To all whom it may concern:

Be it known that we, ARTHUR BATES, ARTHUR ERNEST JERRAM, and JOSEPH GOULDBOURN, subjects of the King of England, residing at Leicester, in the county of Leicestershire, England, have invented certain Improvements in Skiving-Machines, of which the following description, in connection with the accompanying drawings, is a specification, like reference characters on the drawings indicating like parts in the several figures.

This invention relates to certain improvements in machines for skiving leather or similar materials.

In skiving machines as heretofore commonly constructed, one disadvantage has been found to result from locating the skiving knife and grinding devices, together with their operating mechanism, above the bed of the machine whereby the operator's view of the material being skived, was obstructed. In such arrangements, moreover, these parts were more or less exposed and were thereby liable to be injured, or to injure the operator. Another objection to some prior machines was due to the employment of disk-shaped knives which were necessarily rapidly reduced in size by the operation of grinding, and hence rendered unfit for service in a comparatively short time. Another type of skiving machine in common use employs a cylindrical knife, but the same is not only expensive, but is difficult to manufacture and keep in satisfactory working condition. A further disadvantage of this type of skiving machine arises from the fact that the usual feed roll used therewith must necessarily be located within the circumference of the knife, which renders it difficult to remove and replace the knife for repairs or for other purposes, and, moreover, unless the knife is unduly large it is difficult to provide and properly support a feed roll of the desired shape and size within the limit of its dimensions. These and many other disadvantages in existing machines are obviated by this invention as will more fully hereinafter appear.

One important feature of this invention consists in providing a dished or cone-shaped knife which is preferably mounted upon the end of its shaft and with its convexed portion or apex outward. This knife

may be made of thin metal, as for instance, of highly tempered steel, and we prefer to form the same by the stamping process whereby the usual dies, which contain a much greater mass of metal than the blank from which the knife is produced, come in intimate contact therewith and extract the heat with sufficient rapidity to temper it. This obviates the necessity of subsequently subjecting the knife to the usual tempering operation.

Another feature of this invention of importance comprises the combination with a table or suitable work support having an aperture therein, of a dished or cone-shaped knife located below such table and arranged with a portion of its cutting edge projecting through the aperture and its remaining portion sloping downward from the level of the table, and so disposed in relation to the surface thereof that the upper marginal portion of the knife is approximately in the plane of such surface with its cutting edge in position to oppose the work. By this arrangement the knife is out of the way, and furthermore, the grinding instrumentalities and all of the operating mechanism for the knife and grinder may be located within the base of the machine and below the work support, so as to be protected from injury. Such a disposition of parts is furthermore advantageous in that it minimizes all danger of injury to the person of the operator.

In accordance with one feature of this invention the grinding means which we employ are combined with the dished or cone-shaped knife in such a manner as to act upon both surfaces of the knife. Preferably, but not necessarily, these means act simultaneously to grind two convergent bevels upon the knife and thereby to produce, in a very effective manner, a circular cutting edge. But the invention also contemplates the application of such grinding means to any other form of rotary knife than those herein referred to. Preferably, also, such grinding means comprise two co-axial grinding disks that are so arranged as to cooperate in the manner herein stated, though the invention is not necessarily limited to this arrangement.

The invention further comprises the provision of an improved construction for relatively moving the grinding means and the

knife to and from operative grinding position, together with means whereby these parts may be moved together, relatively to the feed roll of the machine. This enables the knife to be removed from such feed roll without necessitating a separate adjustment of the grinding means to move the same out of the path in which the knife travels during such adjustment. Preferably the knife is mounted to move upon an axis that is coincident with the center or axis from which the spherical surface of the knife is generated, so that when the knife is adjusted relatively to the roll, or equivalent feeding device, or when the circumference of the knife is reduced from grinding or wear, the original angular relation of its edge to the work supporting table or surface, as well as to the feeding device, is maintained without appreciable change. We regard this as a very important feature of the present invention.

Preferably the grinding means is also adjustably mounted for movements about an axis coincident with that about which the knife moves, whereby, as the knife is reduced in size the inclination of the bevel or bevels thereon will remain substantially constant. In the arrangement employing two grinding disks to produce bevels upon opposite sides of the knife the disks may, for convenience, be mounted upon the same spindle which is angularly disposed relatively to the knife spindle; and where the knife is of dished or coned form the arrangement may be such that the disks are adjustable toward or from the knife about the point from which the spherical surface of the knife is generated.

Another important feature of the invention consists in the improved means for guiding or controlling the material as it is presented to the knife, the same comprising, in part, a member supported for yielding movement and so mounted that one end thereof will yield more readily than the other. This member, preferably, is in the form of a work supporting and feeding roller, and suitably combined therewith is another member, herein shown as a work presser, which acts as a gage, of improved construction, having capacity for one adjustment, relatively to the first-named member, to determine the length and inclination of the skive or bevel and capacity for another adjustment relatively thereto to determine the thickness of such skive or bevel. Preferably the adjustment for determining the length and inclination of the bevel is effected by arranging a pivotal mounting for such work presser at, approximately, the edge of the surface of the feed roll, and providing means for moving it about its pivot to increase or diminish the space between the presser and the surface of the roll. A convenient arrangement adopted to deter-

mine the thickness of the skive or bevel consists in a support for the work presser, and devices whereby such support and the presser are bodily adjusted at such an angle relatively to the surface of the feed roll that the space between these parts may be increased or diminished to the extent desired without changing the angular relation between their opposing surfaces, as determined by the pivotal adjustment above referred to. By combining these two adjustments precisely the inclination and length of bevel, as well as the thickness of the skiving desired, can be obtained in a very simple and effective manner, and the machine may also be adjusted to accommodate stock of varying thickness. An important feature in this connection consists in mounting the work feeding and supporting member for pivotal movement near one end, and in applying a yielding pressure device to the said member in the vicinity of its pivot to oppose the pressure of the work-pressing member, which is preferably pivotally mounted at or near the opposite or free end of the work feeding member. This arrangement serves to equalize the pressure upon the stock as it is fed to the knife, with the result that all portions of the stock are advanced at an equal speed and the skiving operation is accomplished in an even and regular manner.

Other important features of the invention, including improved details of construction and combinations of parts, will be herein-after more particularly described and claimed.

In the accompanying drawings,—Figure 1 is a front elevation of the machine, with portions of the main frame broken away to show internal parts. Fig. 2 is an end elevation, partly in section, of the machine shown in Fig. 1. Fig. 3 is a plan view drawn to a larger scale than that of Figs. 1 and 2, showing in detail the feed roll, knife and parts associated therewith. Fig. 4 is a section showing a detail of the mechanism for adjusting the knife and grinding devices. Fig. 5 is a section of the feed roll and its supporting means; and Fig. 6 is a perspective view of a detail constituting an element of the mechanism shown in Fig. 5.

Like characters of reference indicate like parts throughout the several views.

The machine comprises a rectangular casing or frame 1 adapted to be supported on a bench or the like, the casing being provided with a lid 3 hinged at 5, in order that the interior parts of the machine may be inspected when desired. The main shaft 7 of the machine is journaled in the lower part of the casing 1 and it is rotated by a power driven pulley 9 loose upon the shaft but capable of being connected therewith by a clutch 11 actuated from a treadle or other

device which is connected to the bell crank lever 13, but not herein fully described as it forms no part of the present invention.

The machine is provided with a skiving knife 15 of dished or conical form as shown, a grinding apparatus 17, 19, therefor, a work-feeding roll 21, and a work guide or presser 23, which parts will now be more fully described. The dished or conical knife 15 may be formed by suitable dies of heat conducting material from a thin blank of steel or other suitable metal, the dies during the forming operation serving to extract the heat with sufficient rapidity from the blank to effect the necessary tempering thereof. The knife thus formed need not be finished upon its surfaces but merely requires a slight bevel to be ground upon both sides to form the cutting edge. The knife 15 is herein shown as secured by a clamping plate 25 upon the upper end of a spindle 27 contained in a sleeve 29 that projects from a casing 31 surrounding the main shaft 7, the knife 15 being driven from the main shaft by a bevel gear 33 thereon which meshes with a similar gear 35 on the lower end of the spindle 27. The axis of the spindle 27 is shown as slightly inclined to a vertical plane, as will appear in Fig. 2, and its inclination can be varied by means of an adjusting device. The adjusting device, as herein shown, comprises a headed bolt 37 threaded into the main casing 1 and engaging a tail piece or extension 39 formed upon the casing 31. A spring 41, secured at one end to the main casing and at its other end to the extension 39 maintains the latter in contact with the bolt 37. The inclination of the spindle 27 may be so adjusted that the edge of the knife 15 projects just above the feed roll 21 and also a short distance beyond the inner side of a slot 43 formed in the lid 3, as shown in Fig. 3.

The grinding apparatus for the knife 15 comprises two disks 17 and 19 which are preferably both secured upon the upper end of a spindle 45 journaled in a sleeve 47 that projects from a casing 49 surrounding the main shaft 7. The grinding spindle 45 is driven from the main shaft 7 by bevel gears 52 and 53 as shown in Fig. 1, from which figure it will be seen also that the two casings 31 and 49 are arranged side by side and are provided with a tongue and groove connection 55 so as to completely inclose the bevel gears which transmit motion from the main shaft 7 to the knife spindle 27 and to the grinding spindle 45.

The disks 17 and 19 are arranged to act, respectively, upon the upper and lower surfaces of the marginal portion of the knife, and as shown in Fig. 2, their distance apart on the spindle 45 in conjunction with the angular relationship of the latter with the knife spindle 27 insures the formation of a

proper cutting edge upon the periphery of the knife.

The grinding apparatus is adapted to be moved into and from grinding position by any suitable means, that selected for illustration consisting of a headed bolt 51 (Fig. 4) which is threaded into a block 57 and bears upon a tail piece or extension 59 formed upon the casing 49. A spring 61 secured to the main casing 1 and also to the extension 59, tends to maintain the bolt 51 and tail piece in engagement.

In order that both the grinding apparatus and the knife 15 may be moved together toward or from the feed roll 21, the block 57 surrounds the bolt 37 and is held against a collar 63 thereon by the action of the spring 61. By this construction upon rotation of the bolt 51 the grinding apparatus will be moved into or from grinding position, while upon rotation of the bolt 37 the grinding apparatus will be caused to simultaneously move with the knife 15 toward or from the feed roll 21. From this arrangement it will be seen that both the grinding apparatus 17, 19 and the knife 15 are yieldingly maintained in working position by the springs 41 and 61.

The feed roll 21 is mounted on a bearing 65 (Fig. 5) said bearing being movable about a pivot 67 the axis of which if extended would intersect the circumference of the feed roll 21 at a plane lying between that of the operative portion of the knife edge and the axis of the feed roll. The feed roll 21 is driven from the main shaft 7 by a bevel gear 39 on said shaft which meshes with a similar gear 69 on a vertical shaft 71 journaled in a sleeved extension of the main frame. The shaft 71 carries at its opposite end a worm gear 73 which meshes with a worm gear 75 on a horizontal shaft 77 to which is connected a floating spindle 79, the latter being coupled to the feed roll. In the machine herein illustrated the feed roll 21 is so mounted as to be capable of yielding during the operation of the machine, as will be hereinafter described, and in order to permit of such yielding the floating spindle 79 is connected with the feed roll 21 by a universal coupling, herein shown as comprising a ball 81 on the end of the spindle 79 which is received in a recess 83 in the hub of the feed roll, and a pin 85 rotatably mounted in the ball 81, and provided with flattened sides that are received in slots 87 in the hub of the feed roll, as shown in Figs. 1, 5 and 6. The opposite end of the floating spindle 79 is similarly connected with a slotted sleeve 89 fast upon the shaft 77.

The pivot 67 of the bearing 65 of the feed roll 21 is mounted in a block 91 adjustably supported on the main casing 1, and the connection between the pivot and the feed roll bearing comprises a slot 93 in the latter as

shown by dotted lines in Figs. 1 and 5. A spring 95 situated within a sleeve 97 threaded into the main casing 1 acts through a plunger 99 and a strut 101 upon the bearing 65 so as to force the feed roll 21 toward the work presser 23. One end of the strut 101 is received within a recess 103 formed in the bearing 65, while the other end is seated in a depression 105 in the plunger 99, the latter having a flange 107 that serves to limit its outward movement by engaging the end of the sleeve 97, as shown by dotted lines in Fig. 1. The force exerted by the spring 95 upon the bearing 65 can be adjusted either 15 by means of a plug 109 threaded into the end of the sleeve 97, or by screwing the sleeve itself up or down in the main casing 1. A lug 111 on the block 91 extends into a slot in the bearing 65 and prevents it from 20 being displaced laterally while permitting it to rise and fall.

The work guide or presser 23 is herein shown as pivotally mounted upon a plate 113 that is provided with a stem 115 received within two perforated bosses 117, 119 on the main casing 1. The stem 115 is screw threaded and a nut 121 thereon and situated in the space between the two bosses 117, 119, provides means whereby the presser 25 23 may be raised or lowered to vary the thickness of the skive and to accommodate work of varying thicknesses. A dowel pin 123 shown by dotted lines in Fig. 1, serves to prevent rotation of the plate 113. The 30 work presser can be moved about its pivot 125 to vary the angle it makes with the edge of the knife so as to obtain the desired angle or width of the bevel on the material between it and the feed roll 21, by means 35 of the handle 127 that projects from a spindle 129 journaled in the plate 113, and provided with an eccentrically mounted pin 131 to engage a slot 133 in an arm extending from the presser 23, as shown in Figs. 1 and 40 45 50 55 60 65 70 75 80 85 90 95 100 105 110 115 120 125 130 135 140 145 150 155 160 165 170 175 180 185 190 195 200 205 210 215 220 225 230 235 240 245 with a work supporting table having an aperture therein, of a rotary dished knife the edge of which is arranged to make a cut extending at an angle to the axis of rotation 5 arranged below said table with a portion of its cutting edge in said aperture and its remaining portion inclined downwardly therefrom.

3. In a skiving machine, the combination 10 with a work supporting table having an aperture therein, of a rotary dished knife, the axis of rotation of which is oblique to the plane of the table and the edge of which is adapted to make a cut extending at an 15 angle to said axis, said knife being located below said table with a portion of its edge in said aperture, and driving mechanism for said knife also located below said table.

4. In a skiving machine, the combination 20 with a work supporting table having an aperture therein, of a rotary dished knife the edge of which is arranged to make a cut extending at an angle to the axis of rotation having a portion of its edge extending 25 in said aperture, grinding devices for the knife, and operating mechanism for said parts, the remaining portion of said knife, and said grinding devices and operating mechanism being located below the level of 30 the table.

5. In a skiving machine, the combination 35 with a work supporting table having an aperture therein, of a rotary dished knife the edge of which is arranged to make a cut extending at an angle to the axis of rotation having a portion of its edge extending in said aperture, a feed roll and operating 40 mechanism for the knife and roll, all of said parts being located below the level of the table.

6. In a machine of the class described, the combination of a work supporting table provided with an aperture constructed to receive a portion only of the edge of a knife, 45 and a skiving knife mounted for movement toward and from said aperture.

7. In a machine of the class described, the combination of a work supporting table provided with an aperture constructed to receive a portion only of the edge of a knife, 50 and a skiving knife below said table mounted for movement toward and from said aperture.

8. In a skiving machine, the combination 55 with a work supporting table provided with an aperture adapted to expose for operation a portion of the edge of a knife, of a dished knife arranged below said table and mounted for movement toward and from said aperture in passing from operative to inoperative position.

9. In a skiving machine, the combination 60 with a work supporting table provided with an aperture, and a feed roll located below

said aperture, of a knife below the table and 65 arranged for movement toward and from said aperture and feed roll.

10. In a skiving machine, the combination 70 with a dished knife, of a supporting spindle therefor mounted for pivotal movement about an axis located at the end of said spindle to permit the knife to move to and from operative position.

11. In a skiving machine, the combination 75 with a dished knife, of a supporting spindle therefor adjustably mounted for pivotal movement about an axis located at the end of said spindle to permit the knife to move to and from operative position, and means for rotating said spindle, said means being 80 operative in any of its positions of adjustment.

12. In a skiving machine, the combination 85 with a table, of a skiving knife and work feeding means arranged for relative movement to bring the edge of the skiving knife into or out of operative relation with the work feeding means and the work-supporting surface of said table.

13. In a skiving machine, the combination 90 with a table, of a feed roll and a knife, said parts being arranged for relative movement whereby the knife is caused to be brought into or out of operative relation with the feed roll, said knife in the last-named position being located entirely below the table. 95

14. In a skiving machine, the combination 100 with a knife having the approximate form of a segment of a sphere, of supporting means therefor arranged to permit movement of the knife about a center corresponding to that from which the spherical surface of the knife is generated. 100

15. In a skiving machine, the combination 105 with a dished knife, of a rotatable spindle therefor mounted for movement about an axis corresponding to the center from which the spherical surface of the knife is generated, and driving means which is operative 110 to rotate said spindle in its several positions of adjustment about said axis.

16. In a skiving machine, the combination 115 with a work supporting table provided with an aperture, of a dished knife, a supporting spindle therefor mounted for pivotal movement beneath said table and arranged to permit the knife to move into and out of operative relation to said aperture, and driving means for said spindle.

17. In a skiving machine, the combination 120 with a rotary knife having a supporting spindle, of grinding disks arranged on opposite sides of said knife and adapted to simultaneously grind two convergent bevels thereon, a spindle for supporting said 125 disks, and a shaft having driving connection with said spindles and about which they are relatively adjustable.

18. In a skiving machine, the combination with a rotary dished knife having a supporting spindle, of grinding disks arranged on opposite sides of said knife and adapted to simultaneously grind two convergent bevels thereon, a spindle for supporting said disks, and a shaft having driving connection with said spindles and about which they are relatively adjustable.
- 10 19. In a skiving machine the combination with a circular knife angularly adjustable about a given axis of a grinding disk supported for movement about the same axis relatively to the knife, said axis intersecting the axes of rotation of said knife and disk.
- 15 20. In a skiving machine, the combination with a dished knife supported for movement about an axis corresponding to the center from which the spherical surface of the knife is generated, of grinding means supported for movement about the same axis.
- 25 21. In a skiving machine, the combination with a knife having a supporting spindle, of a grinding device having a supporting spindle, said spindles mounted for relative pivotal movement about an axis which intersects said spindles.
- 30 22. In a skiving machine, the combination with a knife having a supporting spindle, of a grinding device having a supporting spindle, said spindles being mounted for relative pivotal adjustment about an axis which intersects said spindles, and driving means for the spindles operative in any of their positions of adjustment.
- 35 23. In a skiving machine, the combination with a knife having a supporting spindle, of a grinding device having a supporting spindle, a driving shaft for the spindles, and means whereby the spindles are mounted for adjustment about said shaft.
- 40 24. In a skiving machine, the combination with a knife having a supporting spindle, and a grinding device having a supporting spindle, each of said spindles provided with a gear, of a driving shaft having coöperating gearing, and casings movably mounted upon the driving shaft and having sleeves surrounding said spindles.
- 45 25. In a skiving machine the combination with a work support of a rotary knife and a grinding disk, means for producing relative movement of said knife and disk to bring said members into contact, and means for moving said members simultaneously about a common axis toward and from said work support, said common axis intersecting the axes of said knife and disk.
- 50 26. In a skiving machine the combination with inclined shafts of a knife and grinding device mounted respectively on the upper ends thereof and supported for adjustment relatively to each other, of means for simultaneously adjusting the knife and grinding device, and independent means for adjusting said grinding device.
- 55 27. In a skiving machine, the combination with work feeding means, of a knife and a grinding device, movable supports therefor, controllable devices arranged to act upon said supports to move the knife and grinding device in unison away from the work feeding means, or to move the grinding device alone away from said means, and yielding means for moving said supports toward said means.
- 60 28. In a skiving machine, the combination with work feeding means, of a knife and a grinding device, movable supports therefor provided with extensions, a bolt for engaging the knife support extension having threaded engagement with the frame of the machine and provided with a collar, a block surrounding said bolt below the collar and provided with an internally threaded arm, a bolt fitting said thread and engaging the extension upon the grinding device support, and yielding means for moving said supports toward the work feeding means.
- 65 29. In a skiving machine, the combination with a rotary knife, of a pair of grinding disks mounted upon a common support, and means for moving said disks into simultaneous contact with the opposite sides of the knife to grind two convergent bevels thereon.
- 70 30. In a skiving machine, the combination with a knife and a supporting spindle therefor, of a pair of grinding disks arranged upon opposite sides of the knife and having a supporting spindle, said spindles arranged for movement about an axis, which intersects their longitudinal axes.
- 75 31. In a skiving machine, the combination with a knife having a supporting spindle, of a pair of grinding disks arranged upon opposite sides of the knife and having a supporting spindle, said spindles arranged for adjustments about an axis which intersects their longitudinal axes, and means for effecting such adjustments.
- 80 32. In a skiving machine, the combination with a knife having a supporting spindle, of a pair of grinding disks arranged upon opposite sides of the knife and having a supporting spindle, said spindles arranged for adjustment about an axis which intersects their longitudinal axes, and means for rotating the disks in any of their adjusted positions.
- 85 33. Work feeding mechanism for a skiving machine comprising a work support yieldable vertically and angularly and work pressing means arranged for adjustment relatively thereto to determine the length
- 90 95 100 105 110 115 120 125

and inclination of a bevel and to determine the thickness thereof, said adjustments being effected independently.

34. Work feeding mechanism for a skiving machine comprising a work support yieldable vertically and angularly and work pressing means associated therewith arranged for pivotal adjustment to determine the length and inclination of a bevel and for independent bodily adjustment to determine the thickness thereof.

35. Work feeding mechanism for a skiving machine comprising a bodily and angularly yieldable feed roll, a carrier adjustable relatively thereto, and a presser pivoted to said carrier and angularly adjustable with respect thereto.

36. Work feeding mechanism for a skiving machine, comprising a bodily and angularly movable feed roll, a carrier mounted for adjustment relatively thereto, a presser pivoted to said carrier and provided with an arm, and a lever supported upon the carrier and operatively connected with said arm.

37. In a skiving machine, the combination of a feed roll, pivotal means for supporting said roll near one end, yielding means for holding the roll in engagement with the work, and means for adjusting the pressure of said yielding means.

38. In a skiving machine, the combination with a feed roll, of a yielding support therefor, the parts being so arranged that one end of the roll will yield more readily than the other, and means for adjusting the effective pressure of said support against the work without varying the position of the support.

39. In a skiving machine, the combination with a feed roll and a bearing therefor constructed to have pivotal engagement with a fixed part of the machine, of yielding means to effect such engagement.

40. In a skiving machine, the combination with a feed roll, of a pivotal support located near one end of the roll, and yielding means located near said support and acting to maintain the roll in engagement therewith.

41. In a skiving machine, the combination with a feed roll supported for pivotal movement near one end, of yielding means acting to exert an upward pressure upon the roll in the vicinity of its pivotal support and adjustable devices to vary such pressure.

42. In a skiving machine, the combination with a feed roll, of a bearing therefor having a pivotal connection with the machine frame near one end of the roll, a strut engaging the bearing near said connection, a spring-pressed plunger acting upon said strut, means for limiting the movement of said plunger, and a sleeve secured to the

frame for housing the plunger and its spring.

43. In a skiving machine, the combination with a feed roll supported for yielding movement near one end, of a work presser 70 associated therewith and supported for pivotal adjustment near the opposite end of the feed roll.

44. In a skiving machine, the combination with a knife, of a feed roll having a bearing 75 mounted for adjustment about a pivotal axis within the circumference of the roll the extension of which axis intersects the periphery of the feed roll in a plane located between the cutting edge of the knife and the 80 axis of said roll.

45. In a skiving machine, the combination with a feed roll and a bearing therefor pivoted to the frame of the machine on an axis located near the end of the roll and lying 85 in a transverse plane between the surface of the roll and its axis, of a work presser supported for pivotal movement near the opposite end of the feed roll.

46. In a skiving machine, the combination 90 with a feed roll having a pivotal support near one end, of yielding means acting upon the roll arranged near said support, and a work presser associated with the roll and pivotally supported near its opposite end. 95

47. In a skiving machine, the combination with a feed roll pivotally supported near one end, of adjustable yielding means to act upon the roll arranged near said support, and a work presser associated with the roll 100 and pivotally supported near its opposite end.

48. In a skiving machine, the combination with a feed roll, a bearing therefor, and means whereby said bearing is supported for 105 pivotal movement to a fixed part of the machine, yielding means acting upon the bearing to sustain the roll against the pressure of the work, and means for preventing lateral displacement of the bearing. 110

49. In a skiving machine, the combination with a casing and a lid hinged thereto, said lid having a slot therein, of a dished skiving knife and its operating mechanism inclosed within the casing, said knife being arranged below said lid and supported for movement to project a portion of its edge through said slot, or to be withdrawn therefrom. 115

50. In a skiving machine, the combination with a work supporting table having an aperture therein, of a dished knife arranged with a portion of its cutting edge in said aperture and its remaining portion entirely below said table and inclining downwardly from the surface thereof, said knife being 120 movable toward and from said aperture. 125

51. In a skiving machine, the combination with a knife having a supporting spindle, of a grinding device having a supporting spindle, said spindles being mounted for 130

pivotal movement about an axis located at their inner ends.

52. In a skiving machine, the combination with a knife having a supporting spindle, 5 of a grinding device having a supporting spindle, said spindles being mounted for independent pivotal movements about an axis located at their inner ends.

53. In a skiving machine, the combination 10 of a feed roll having a sleeved extension, a stem upon which said extension is rotatably supported, said stem having a head pivotally supported to the frame near one end of the roll and provided with a recess in the vicinity of its support, and a spring-actuated plunger provided with a stem seated in said recess.

54. In a skiving machine the combination with a work supporting table having an 20 aperture therein of an inclined rotary shaft located below said table, and a dished knife carried on the upper portion of said shaft, said knife having a portion of its cutting edge extending into said aperture.

25 55. In a skiving machine the combination with a work supporting table over which

the work is fed of a dished knife having a portion of its edge in position to meet the on-coming work, all of the remaining portion of the knife sloping downward below 30 the table.

56. In a skiving machine the combination with a work supporting table having an aperture therein of a knife having the approximate form of a segment of a hollow 35 sphere arranged below said table with a portion of its edge in said aperture.

57. In a skiving machine the combination with a dished knife having its convexity uppermost of a feed roll located below said 40 knife and arranged to yield, a work presser and means for adjusting the angular position of said presser.

In testimony whereof we have signed our names to this specification in the presence of 45 two subscribing witnesses.

ARTHUR BATES.
